United States Patent Office.

RUSSELL HATHAWAY, JR., AND JOEL D. STETSON, OF FAIR HAVEN, MASSACHUSETTS, ASSIGNORS TO THE AMERICAN TACK COMPANY, OF SAME PLACE.

Letters Patent No. 90,536, dated May 25, 1869.

IMPROVED MACHINE FOR FINISHING GALVANIZED TACKS.

The Schedule referred to in these Letters Patent and making part of the same.

To all whom it may concern:

Be it known that we, RUSSELL HATHAWAY, JR., and JOEL D. STETSON, of Fair Haven, in the county of Bristol, and in the State of Massachusetts, have invented certain new and useful Improvements in Machine for Trimming and Galvanizing Tacks, Nails, &c.; and do hereby declare that the following is a full, clear, and exact description thereof, reference being had to the accompanying drawings, and to the letters of reference marked thereon.

The nature of our invention consists in the construction and arrangement of a machine to be used for the purpose of throwing off superfluous metal from tacks, nails, and other articles that have been covered with tin, lead, zinc, &c.

In order to enable others skilled in the art to which our invention appertains, to make and use the same, we will now proceed to describe its construction and operation, referring to the annexed drawings, which form a part of this specification, and in which—

Figure 1 is a vertical section, and

Figure 2, a plan view.

A represents the frame of the machine, the top of which is provided with a circular opening of suitable size.

In this opening is secured a metal cylinder, B, which extends a suitable distance above and below the top of the frame A, said cylinder being, however, open both at top and bottom.

On the rear side of the frame A is fitted a metal plate, C, which extends a certain distance below the lower edge of the cylinder B.

An inclined metal plate, D, extends from the rear of the frame forward, and projects in front of the frame, said plate being turned up, so as to form sides, which narrow toward the front end of the plate, thus forming a spout, E.

The upper rear edge of the plate D is placed a short distance below the lower edge of the plate C, leaving an aperture, a, between the two, across the whole back of the frame.

From the front side of the frame A, commencing at the lower edge of the cylinder B, an inclined plate, F, extends, toward the rear, to within a short distance of the plate D, leaving an aperture, b, between the lower rear edge of the plate F and the plate D. There is also a space left between the lower rear edge of the plate F and the upper rear edge of the plate D, as shown in fig. 1. The plate F is also provided with turned-up sides, which, however, extend downward entirely to the plate D.

Through the sides of the frame A is placed a shaft, I, which, on one end outside of the frame, is provided with a pulley, G, from which pulley a belt will lead to some machinery close at hand.

At a suitable point on the shaft I, inside of the cylinder A, is placed a mitre-wheel, H, which gears with another mitre-wheel, J, placed on the lower end of a vertical shaft, L, said shaft having its bearings in a cross-bar, K, inside of the cylinder, in such a manner that the shaft will be exactly in the centre of said cylinder.

On the shaft L, above the cross-bar K, is placed a disk, M, which has a flange, d, projecting upward across its centre, and is so placed that it shall be immediately under a cross-bar, N, which is secured to the upper edges of the cylinder B, across its centre.

To the centre of the cross-bar N is secured a hopper, O, the cross-bar being provided with a hole, or opening, to allow any articles placed in said hopper to pass through.

Articles, such as tacks, nails, &c., having been put into molten metal, require to be thrown out violently against some surface, to free them from superfluous portion that adheres. By dropping such articles, taken from the molten metal, down the hopper O, they fall on the disk M, which is driven at a high rate of speed, and are thrown off violently by the centrifugal force imparted to them by the revolving disk.

Having thus fully described our invention,

What we claim as new, and desire to secure by Letters Patent, is—

1. A machine so constructed that articles that have been dipped in tin, lead, zinc, &c., may be freed from the superfluous metal adhering to them, by being thrown violently against some surface, substantially as herein set forth.

2. The arrangement of the frame A, cylinder B, vertical plate C, and inclined plates D and F, substantially as shown and described.

3. The arrangement of the horizontal shaft I, mitre-wheels H and J, vertical shaft L, disk M, and hopper O, all substantially as shown and described.

In testimony that we claim the foregoing, we have hereunto set our hands, this 4th day of February, 1869.

RUSSELL HATHAWAY, JR.

JOEL D. STETSON.
